UNITED STATES PATENT OFFICE.

SAMUEL B. SEXTON, OF BALTIMORE, MARYLAND.

DESIGN FOR A FIRE-PLACE STOVE.

Specification forming part of Design No. 6,877, dated September 9, 1873; application filed August 4, 1873.
[Term of Patent 14 years.]

To all whom it may concern:

Be it known that I, SAMUEL B. SEXTON, of Baltimore, in the State of Maryland, have invented a new Design for Fire-Place Stoves, of which the following is a specification:

The essential parts of my new design are, first, an ornamental body gradually expanding upward from the top of the base to about the level of the top of the fuel-chamber; second, an ornamental dome-shaped top surmounting the combustion-chamber; third, a protuberance from the front upper portion of the dome, having a vertical face for the reception of the door, and a horizontal top for the reception of an ornamental water-urn.

In the accompanying photographs, Figure 1 is a front view of my stove in position in the fire-place. Fig. 2 is a side view of the stove detached.

The base A may have any convenient form. The body B, or outer shell of the fire-pot, expands gradually upward from the top of the base to a cornice, C, from which springs a dome, D, forming the top of the stove. A

projection or protuberance, E, in the front part of the dome forms a vertical or nearly vertical frame for a windowed door, F, and on its horizontal top supports an ornamental water-urn, G. The surfaces may be figured or ornamented in any preferred manner.

The name of the stove—"The Bituminous-coal Burner"—will be cast upon the front of the stove.

The following is claimed as new:

1. The body B, flaring upward and ornamented with paneled scroll-work, substantially as shown.
2. The dome D springing from the cornice C, and ornamented with flutes and bead-work, substantially as shown.
3. The combined design of the vertical door F and dome-shaped top D, substantially as shown.

S. B. SEXTON.
